ROTARY ATOMIZER AND GAS MIXER

Original Filed March 19, 1931

UNITED STATES PATENT OFFICE

2,015,871

ROTARY ATOMIZER AND GAS MIXER

John D. Ross, Brewer, Maine

Application March 19, 1931, Serial No. 523,689
Renewed August 1, 1934

5 Claims. (Cl. 48—180)

- This invention relates to a rotary atomizer and gas mixer adapted for installation between the outlet pipe of the carburetor and the intake manifold of an internal combustion engine for the purpose of completely atomizing the explosive charge delivered from the carburetor to the end that said charge may be delivered to the cylinders of the engine in a form best suited for instant combustion.
10. Heretofore such fuel atomizing devices with which I am familiar have all operated upon the principle of mechanically agitating the combustible charge delivered by the carburetor. One characteristic feature of my invention is that I provide for admitting into the stream of the charge a supply of atomizing oxygen the function of which is to more finely break up the charge delivered from the carburetor. This supply of atomizing oxygen is controlled by and in the movement of the actuating means for the throttle valve of the carburetor and hence its delivery into the stream of the charge is regulated automatically according to the speed of the engine.
25. Other features of my invention will appear more particularly hereinafter.

As illustrative of the principles involved I show in the accompanying drawing a device which I have found satisfactory under actual service conditions and well adapted to the requirements of manufacture.

In the drawing:—

Fig. 1 is a fragmentary side elevation at the intake side of an internal combustion engine equipped with a rotary atomizer and gas mixer in accordance with my invention, the throttle valve of the carburetor being shown as retarded for idling.

Fig. 2 is a view similar to Fig. 1 but showing the throttle valve advanced for speed.

Figs. 3 is a view of my rotary atomizer and gas mixer removed and indicating in dotted lines an optional connection whereby a supercharging medium under pressure may be admitted into the mixture stream.

Fig. 4 is a top plan view of my rotary atomizer and gas mixer removed.

Fig. 5 is a bottom plan view thereof.

Figs. 6 and 7 are sections on the lines 6—6 of Fig. 4 and 1—1 of Fig. 5, respectively, and

Fig. 8 is a detail view of the bladed rotors of my unit removed.

Referring to Fig. 1, I have indicated generally at 1 the carburetor of an internal combustion engine of conventional type and at 2 the

outlet pipe thereof from which the combustible charge is delivered into the intake manifold 3 of the engine.

Mounted in any desired location intermediate of the carburetor and intake manifold and preferably at the meeting ends of the carburetor outlet pipe 2 and manifold pipe 3 is my novel vaporizing and atomizing unit. Such unit is assembled in the relation shown by means of the usual studs 3' which unite the pipes 2 and 3 10 and comprises a generally cylindrical casing consisting of an upper casing forming member 4 and a bottom casing forming member 5. When assembled together as shown in Figs. 3, 6, and 7 the members 4 and 5 define a generally spherical chamber 6 which is open at either end so as to permit the explosive charge from the pipe 2 to pass freely therethrough into the pipe 3.

As contemplated herein, each of the casing members is internally formed as a dished surface 7 so that when the casing members 4 and 5 are assembled together the resultant chamber 6 is a chamber of greater diameter than the diameter of the pipe 2 and hence affords a reservoir for a reserve supply of mixture of combustible 25 charge for emergency demand.

The members 4 and 5 may be fastened to each other in any desired manner. As here shown, each member is provided with a circumferential flange 8 adapted to abut the similar flange of 30 the opposite member and fastened at such meeting flanges in any suitable manner as by the screws 9.

During its passage through the chamber 6 the mixture is subjected to the vaporizing and atomizing action of one or more bladed rotors mounted within said chamber in the longitudinal axis thereof. As here shown I provide two superposed rotors, viz., a lower rotor 10 and an upper rotor 11 spaced from each other and from the respective ends of the chamber 6.

The rotors 10 and 11 are assembled upon a stationary shaft 12 which is reduced at its ends and stepped in suitable bearings 13 and 14 at the ends of the respective casing forming members. 45 The bearings 13 and 14 may be constituted by webs of material left when the upper and lower open ends of the casing forming members were formed whereby to provide for the free passage of the explosive charge through the chamber.

The rotors 10 and 11 are spaced from each other and from the bearing webs 13 and 14 by three spacing collars 15 which are assembled on the shaft 12 as best shown in Figs. 6 and 7.

The purpose of spacing the rotors from each 55

other and from the ends of the casing is to eliminate any whistling or singing effect of the rotors in action and also to avoid any danger of choking the passage of the mixture through the casing and thus causing a hitching or retarding of the engine (not shown). In this connection it is to be noted that the under face of the web 14 is beveled as indicated at 16 in Fig. 5 whereby to split the incoming charge from the carburetor.

The blades of the individual rotors are of angular cross-section presenting a generally vertical face 17 or 17' disposed substantially in the axis of rotation of the rotors and an inclined face 18 or 18' inclined to such axis, the knife edges of the blades of each rotor being disposed downwardly whereby most effectively to compel the rotors to be revolved under the action of the explosive charge being drawn therewith by the suction of the engine. It will be noted, however, that the vertical face of the blades of the lower rotor are offset with relation to the corresponding faces of the blades of the upper rotor. The purpose of this is to compel the rotors to revolve in opposite directions as indicated by the arrows A in Fig. 8.

The inclined faces of the blades compel the rotation of the rotors and the perpendicular faces of the blades serve as breaker surfaces for the purpose of thoroughly atomizing the explosive charge, as distinguished from prior art devices in which the blades are set obliquely to the direction of travel of the mixture and simply act as cutting edges rather than broadside smashing surfaces. This eliminates any tendency of the rotors to lift upwardly under the pressure of the explosive charge with resultant wear on the bearings of the rotors, in my construction the rotors simply floating without uplift when the engine is running at speed.

The angle of inclination of the inclined surface 17' of the upper rotor is a somewhat greater angle than that of the lower rotor blades whereby the upper rotor rotates at higher speed than the lower rotor. The purpose of this construction is to insure the maximum atomization of the mixture.

In order completely to break up the explosive charge from the carburetor I provide for the admission of a supply of atomizing oxygen into the atomizing chamber according to the speed of the engine. For this purpose one of the casing forming members, preferably the lower member, is cored to provide an oxygen admission passage 19, delivering substantially tangentially against the angular faces 18 of the lower rotor and from such rotor being deflected as indicated by the arrows B in Fig. 8 against the angular faces 18' of the upper rotor.

The admission of such atomizing oxygen into the chamber is controlled by a valve lever 20 adapted to be operated by the same operating means which operated the throttle valve 21 of the carburetor. The valve lever 20 is pivoted between its ends as at 22 exteriorly of the lower casing forming member 5 with its forward end normally closing the passage 19, said end being yieldingly urged towards such closed position by a spring 23. As here shown such spring is a coil spring confined between the rear end of the valve lever 20 and the adjacent wall portion of the casing 5.

The valve lever 20 is a cam lever, and is actuated by engagement by the rotor arm 24 for the throttle valve 21. Such arm 24 is fixed as at 25 to the throttle valve and is operated from

the dash through any suitable motion transmitting connections of which the operating rod 26 only has been shown. The action is a sliding action of the arm 24 over the lever 20 and its effect when the throttle valve is opened as shown in Fig. 2 is to depress the rear end of said lever against the action of the spring 23 thereby raising the forward end of the lever 20 and uncovering the inlet passage 19 for the admission of the atomizing oxygen into the chamber 6.

When the throttle is retarded as shown in Fig. 1, the arm 24 is at the other extreme of the stroke, releasing the lever 20 which under the action of the spring 23 returns to close the passage 19. This action is entirely automatic and eliminates racing the motor when idling. The admission of oxygen through the passage 19 being regulated from the same operating means which opens and closes the throttle valve of the carburetor such oxygen is admitted into the atomizing chamber in direct proportions to the needs of the engine at all speeds.

As an optional equipment the atomizer may be provided with means whereby a supply of super-charging medium, as for example, steam or other gaseous vapors under pressure may be admitted into the mixture charge whereby to give greater power than the carburetor alone can supply. To this end I indicate at 27 in Figs. 1 and 2 a passage cored into lower casing forming members and opening into the chamber 6, with which passage a suitable pipe connection as at 28 in Fig. 3 may be made where it is desired to use the pressure super-charged feature. Obviously the pipe 28 may be utilized for the purpose of admitting a lubricating fluid as for example oil into the explosive charge whenever needed. When the connection 28 is not in use it is removed and the opening 27 is closed by any suitable plug or the like.

While particularly intended for use in an internal combustion engine, it will be understood that my invention is not confined to such use alone, and hence the foregoing discussion is to be taken as purely illustrative and in no way limiting. As will be obvious the principles of my invention are capable of application to a wide variety of installations wherever it is desired to vaporize or atomize any fluid or gas, as for example, in oil-fired furnaces, oil burning engines of the Diesel type, and in the blending of certain fluids.

Similarly various modifications in structure and assembly may be resorted to within the spirit and scope of my invention as defined by the appended claims.

What I therefore claim and desire to secure by Letters Patent is:

1. A rotary atomizer adapted to be mounted between the mixture outlet pipe of the carburetor and the intake manifold of an internal combustion engine and comprising a casing, a pair of bladed rotors mounted in said casing, the blades of which present respectively a surface which is parallel to the axis of rotation of the rotors coaxially and an opposed surface which is inclined with respect to such axis.

2. A rotary atomizer adapted to be mounted between the mixture outlet pipe of the carburetor and the intake manifold of an internal combustion engine and comprising a casing, a pair of bladed rotors mounted in said casing, the blades of which present respectively a surface which is parallel to the axis of rotation of the rotors and a surface which is inclined with respect to such

axis, the inclined surfaces of one set of rotor blades being disposed in angularly intersecting relation to the inclined surfaces of the blades of the other rotor.

5. 3. A rotary atomizer adapted to be mounted between the mixture outlet pipe of the carburetor and the intake manifold of an internal combustion engine and comprising a casing, a pair of bladed rotors mounted in said casing, the blades 10 of which present respectively a surface which is parallel to the axis of rotation of the rotors and a surface which is inclined with respect to such axis, the inclined surfaces of one set of rotor blades being disposed in angularly intersecting relation to the inclined surfaces of the blades of the other rotor and the blades of both rotors all being disposed with their narrow ends extending in the same direction, said casing having an 15 air inlet opening thereto substantially tangentially to the inclined blade surfaces of one of said rotors, and a valve for said inlet.
15. 4. A rotary atomizer adapted to be mounted between the mixture outlet pipe of the carburetor and the intake manifold of an internal combustion engine and comprising a casing, a pair of 20 blades mounted in said casing, the blades being disposed with their narrow ends extending in the same direction.
20. 5. A rotary atomizer adapted to be mounted between the mixture outlet pipe of the carburetor and the intake manifold of an internal combustion engine and comprising a casing, a pair of

bladed rotors mounted in said casing, the blades of which present respectively a surface which is parallel to the axis of rotation of the rotors and a surface which is inclined with respect to such axis, the inclined surfaces of one set of rotor blades being disposed in angularly intersecting relation to the inclined surfaces of the blades of the other rotor and the blades of both rotors all being disposed with their narrow ends extending in the same direction, said casing having an 10 air inlet opening thereto substantially tangentially to the inclined blade surfaces of one of said rotors, and a valve for said inlet.

5. A rotary atomizer adapted to be mounted between the mixture outlet pipe of the carburetor 15 and the intake manifold of an internal combustion engine, comprising a casing, a bladed rotor mounted in said casing, each blade of said rotor having a flat side and an opposed beveled side, the flat side of one blade facing the beveled side 20 of the next adjacent blade.
